POWER CLAMPING DEVICE

Guy E. Swartz, Detroit, Mich.

Application March 7, 1932, Serial No. 597,204

1 Claim. (Cl. 77—62)

My invention relates to clamping devices, such as jigs, etc. and to power means to operate the devices and locking means to normally prevent movement of the clamp in such devices.

5 In such devices it is quite desirable and, in many instances, quite necessary that the clamp thereof be normally held or locked in a definite position, either in clamping or unclamping positions and that the lock be easily released when it is desired 10 to move the clamp. In power driven devices this feature is even more desirous than in hand driven devices in that an operator has more direct volitional control of the clamp operating means than in power operated devices wherein the clamping 15 and unclamping is done by power other than manual power.

An object of my invention is to provide a simple, inexpensive, easily operable and efficient power driven clamping device having a power operated 20 clamp, a self locking, self releasing locking means to retain the clamp in any position into which it may be moved, in either direction, and a simple and efficient control means for the clamp driving or moving means.

25 Other objects will be pointed out in this specification or will become obvious or will suggest themselves upon an inspection of this specification and of the accompanying drawing forming part of this specification.

30 I attain these objects by the mechanism illustratively shown in the accompanying drawing mentioned above forming part of the specification, in which drawing:

Fig. 1 is a section of a power clamping device 35 embodying my invention.

Fig. 2 is a vertical partial section taken on line 2—2 of Fig. 1 showing relation of one of the gears to one of the posts and to the cylinder.

Fig. 3 is a vertical partial section on a larger 40 scale taken on line 3—3 of Fig. 1 showing relation of another gear to the other post.

Fig. 4 is a vertical partial section on a larger 45 scale taken on line 4—4 of Fig. 1 showing relation of the third gear to the cylinder.

Fig. 5 is a transverse section on a larger scale 50 taken on line 5—5 in Fig. 2 showing the shaft and locking means structure more clearly.

Fig. 6 is a section on a larger scale of the locking 55 releasing mechanism of Fig. 1. The section is taken on the line 6—6 of Fig. 5.

Fig. 7 is a plan view of a control valve for the power means.

Fig. 8 is a section of the control valve of Fig. 4.

Similar reference characters refer to similar 55 parts throughout the views.

The drawing shows and this specification specifically describes one type of power clamping device, but it is obvious that the invention can be applied in different structures.

The device specifically shown and described 5 comprises as follows:

The base A may be of any convenient form for direct reception of work or adapters and of sufficient strength for whatever load may be imposed thereon.

10 The clamping plate B may be of any form and may have guide bushings therein or adapters thereon as conditions may impose. The ribs 10 may be provided to stiffen or strengthen the plate B especially when heavy loads are brought thereon near the middle thereof.

15 The posts 11 and 12 are secured to the plate B and depend therefrom and the lower ends thereof are respectively guided in the base A. The rack teeth 13 and 14 are provided on the lower part of the respective posts.

The shaft C has the ends thereof journaled in the base. The sleeve 15 is journaled on the shaft.

20 The teeth 16 are provided on the shaft C to mesh with the teeth 13 on the post 11. The teeth 17 are provided on the shaft to mesh with the teeth 14 on the post 12. The teeth 18 are provided on the sleeve at a place intermediate the teeth 16 and 17 to mesh with the teeth 19 on the piston rod 29.

25 The cylinder D is secured to the base and is held against longitudinal movement thereof by the transverse key 21. The piston 22 is in the cylinder as usual and the piston rod 23 is secured to the piston as usual and extends out through one end of the cylinder and has the above-mentioned teeth 19 on the outer part thereof. The axis of the cylinder is so placed that the teeth 19 mesh with the teeth 18 on the sleeve.

30 The control means comprises the two way valve 24 having the exhaust port 25, the port 26 with the pipe 27, the port 28 with the pipe 29 and the intake port 30 with the feed pipe 31. The pipe 27 leads into one end of the cylinder and the pipe 29 leads into the other end. The rotatable part 32 of the valve has corresponding ports. Each two of these ports at right angles to each other are connected by the passage ways 33 and 34.

35 The control valve is shown for better illustration as being separate from the device but is connected thereto by the pipes 27 and 29. The control valve can be placed within the base if desired and the operating handle 35 thereof can project 40 out through the wall of the base.

- The locking mechanism E may be supported on the inside of a wall of the base as shown.
- The casing 36 of the locking mechanism has the bore 37 therein. The rotor or operating member is keyed onto the shaft C by means of the key 38 and rotates the shaft and is journaled in the bore 37. The cover 39 is a part of the sleeve and closes one end of the casing and holds the locking members therein.
- 10 The projections 40, 41, and 42 are provided on the rotor on the respective sides of the projections to form the grooves 42 and 43a, 44 and 44a, and 45 and 45a and the rollers 46, 47, 48, 49, 50, and 51 are disposed in the corresponding grooves 15 between the bottoms thereof and the bore 37 in the casing and also adjacent to the corresponding side walls 52, 53, 54, 55, 56, and 57 of the projections.
- 20 The bottom of each groove forms an inclined plane in relation to the bore 37 on each side of the corresponding projection so that each groove forms a pocket which is deepest at the projection and diminishing in depth from the projection toward each end thereof.
- 25 The springs 58, 59, and 60 extend through the prongs and are provided between the corresponding pairs of rollers and normally tend to separate the same and move them into the less deep portions of the grooves and thereby lock the shaft against self rotation in either direction.
- 30 The driving prongs 61, 62, and 63 extend from the flange or cover 39 into the corresponding grooves outwardly adjacent to the corresponding rollers and have holes therein, longitudinally thereof to loosely receive the rollers 64 to centralize the rotor in the casing.
- 35 The device shown and described is intended to be operated pneumatically but other fluidic power means may be used with corresponding modifications if necessary. A hydraulic power means may be used in the device shown and described.
- 40 The pipes to the cylinder are shown comparatively large for quick action. In hydraulic operated devices it may be necessary to increase the size of the pipes to attain quicker action in the device.
- 45 In operation, starting from the positions of the various elements as shown in Fig. 1, air from a suitable source enters the valve through the port 50 30 by means of the pipe 31, passes through the passage-way 34, then through the port 26 into the pipe 27, and then into one end of the cylinder and thereby moves the piston in the direction of the arrow and rotates the sleeve through the teeth mesh between the piston rod and the sleeve.
- 55 This rotation of the sleeve rotates the prongs 61, 62, and 63 on the cover 39 to contact the rollers 46, 48, and 50 respectively and thereby moves these rollers out of their locking position and against the walls 43, 44, and 45, respectively, and thereby rotates the shaft through the keyed relation between the rotor and the shaft. Rotation of the shaft rotates the teeth 16 and 17 and moves the posts 11 and 12 due to the teeth mesh between them and thereby moves the clamping plate. Reversal of the shaft engagement on the posts from front to rear or reversal of the piston rod engagement from the top to the bottom of the teeth on the sleeve will result in the clamping plate moving in the opposite direction.

As soon as the power means stops operating and the shaft comes to rest in any rotative position thereof, the springs move the rollers into locking positions and thereby lock the shaft against self rotation due to pressure brought onto the clamping plate and thereby locks the clamping plate against self movement in either direction.

Normally, the pressure in the cylinder holds the clamping plate against reverse movement from any position moved into as long as the power is turned on but when the power fails or is turned off in some manner or fails in some manner, the locking mechanism prevents movement of the clamping plate in either direction.

The power means retains the clamping plate in any position, as in a work clamping position for instance, and moves the clamping plate to follow up in case the work becomes loose under the clamp during operation on the work.

A reversal of the power means in the cylinder, as for unclamping of work for instance, cause reversal of the operation described above in substantially the same manner.

The round rollers shown and described may be replaced by flat faced shoes.

I am aware that clamping devices have been made prior to my invention and, therefore, I do not claim the same broadly but I am not aware that such devices have been made prior to my invention with fluid power means to operate the clamp and with automatic locking means to retain the clamp in any position thereof when the same is not operated by the power means and to automatically release itself when the power means starts moving the clamp.

Therefore, I do not claim clamping devices broadly, but I do claim broadly the operating means and the control means and the locking and releasing means.

Since my invention is applicable to clamping devices different than the one specifically shown and described herein and, since I am aware that changes and modifications can be made in the parts specifically shown and described and in the arrangements thereof within the scope and intent of my invention and of the appended claim, I do not limit myself to the precise application of my invention as shown and described nor to the precise structure and arrangement of elements or parts as shown and described.

I claim:

A work clamping device comprising a base, a work clamping plate movable toward and away from said base for work clamping and unclamping, a post depending from said plate and guided in said base and having a rack thereon, a power cylinder in said base to move said plate oppositely, a piston rod extending from said cylinder, teeth on said piston rod, a shaft journaled in said base, teeth on said shaft in mesh with said teeth on the piston rod, teeth on said shaft in mesh with said rack, and a control means for the clamping and unclamping comprising a valve and an operating handle thereon to move the valve to admit fluid pressure to one end of said cylinder and at the same time exhaust from the other end thereof.

GUY E. SWARTZ.
